Wilmer R. Schultz, Emmaus, Pa. 18049

Filed Apr. 1, 1974, Ser. No. 456,635

Term of patent 14 years

Int. Cl. D6—06

U.S. Cl. D6—194

FIG. 1 is a perspective view of the combined armrest, backrest support and clamp down element for a stadium seat showing my new design;

FIG. 2 is a side view of the combined armrest, backrest support and clamp down element for a stadium seat illustrated in FIG. 1, the opposite side being a mirror image and having substantially the same appearance;

FIG. 3 is a top plan view of the combined armrest, backrest support and clamp down element for a stadium seat;

FIG. 4 is a front view of the combined armrest, backrest support and clamp down element for a stadium seat; and

FIG. 5 is a rear view of the combined armrest, backrest support and clamp down element for a stadium seat.

I claim:

The ornamental design for a combined armrest, backrest support and clamp down element for a stadium seat, as shown and described.
